CONTROLLABLE TRUCK LOCK FOR
CRAWLER TRACTORS

Cecil E. Jones, Lima, Ohio

Application October 20, 1941, Serial No. 415,696

12 Claims. (Cl. 188—30)

This invention relates to controllable truck locking mechanism for crawler tractors of the type commonly used to mount load handling equipment such as power shovels, cranes and the like. Such truck locks are of use in preventing undesired movement of the machine on the ground, especially during operation of the machine, as in digging with a power shovel.

For the purpose above specified it has been known to employ ratchet devices having four positions of adjustment providing, respectively, for locking of the crawler truck against movement alternatively in the forward or backward directions, simultaneous locking against movement in both directions, and freeing of the truck for movement in either direction.

Various of the prior ratchet mechanisms are subject to disadvantages, such as unreliable or inaccurate operation; impossibility of or inconvenience in initial adjustment or in subsequent adjustment to compensate for wear; and undue multiplication of actuating and control parts, such as links and the like.

It is with these difficulties that the present invention is principally concerned, the arrangement hereof being unusually simple in structure and operation, notwithstanding that provision is made for four different normal operating settings, as well as adjustment, and further being exceptionally rugged, so as to effectively carry the heavy loads of service.

In accordance with another aspect of the invention, provision is made for adjustment of the positions of the ratchets with reference to each other and with reference to the control member, whereby proper setting of the ratchets may initially be provided and may be maintained.

Although the ratchet mechanism and control therefor, as provided by this invention, is applicable to many different situations, the arrangement is peculiarly suited to power machinery, such for example as shovels and cranes, for reasons brought out more fully hereinafter in the following description, referring to the accompanying drawings, which illustrate the invention in a typical application to a load handling machine mounted on a crawler tractor.

In the drawings—

Figure 1 is an end view of portions of a power handling machine, with parts shown in section in the transverse vertical plane containing the center pin mounting of the rotating base of the machine;

Figure 2 is an enlarged view of some parts

shown in Figure 1, this view being taken in the same direction as Figure 1;

Figure 3 is a view on the scale of Figure 2 but taken at right angles to Figure 2 and illustrating many of the parts in vertical section; and

Figures 4 and 5 are views of some parts taken similarly to Figure 3 but illustrating different operating positions.

Referring first to Figure 1, the outline of a pair of crawler treads 6—7 is shown in dot and dash lines. These treads are associated with a crawler truck generally indicated at 8, which truck in turn serves to support the superimposed cab and machinery, including the power plant, for which purpose a rotating base 9 is mounted on the truck by means of a center pin 10 and rollers (not shown) which ride on track 8a, so that the entire upper part of the machine may be rotated with reference to the truck and treads 8 and 6—7.

The machine is adapted to be driven on the ground through the vertical propel shaft 11 which carries a gear 12 at its upper end for co-operation with driving mechanism which need not be considered herein. At its lower end shaft 11 carries a bevel gear 13 meshing with bevel gear 14 mounted on the central section 15 of the horizontal propel shaft.

Clutch devices, one of which is generally indicated at 16, serve to couple shaft 15 with shaft extensions 15a and 15b which extensions, in turn, are connected with the tread sprockets (not shown) usually through a chain drive, these parts not being illustrated in detail herein since they form no part of the present invention per se. It may be noted, however, that the clutch units 16 are provided primarily for the purpose of steering, this function being achieved by control mechanism adapted alternatively to engage one or the other of the clutches 16 so as to drive one or the other of the treads 6 and 7. Ordinarily, each device 16 has three positions of adjustment. In one such position, the drive is transmissible therethrough to the crawler sprocket at that side of the machine, in another position the clutch is disconnected from the central shaft 15 and the associated shaft extensions (15a or 15b) is locked as against movement, and in the third position, usually intermediate the first two, the shaft extension is neither locked nor coupled to the drive.

Control of the clutch units is secured by a lever 17 connected with the vertical push-pull member 18 extended through the center pin mounting and coupled with arm 19 mounted on

the control shaft 20, from which suitable connections (not shown) are extended to the clutch units at opposite sides of the machine. As is known in this art, with this control, the driving sprockets for both treads may be actuated, or either one of said sprockets alone may receive power, the other being either locked or left free. Steering in one direction or the other is thus secured.

With the foregoing general features of construction in mind, attention is now directed to the ratchet locking mechanism as provided in accordance with this invention. Horizontal propel shaft 15 carries a ratchet wheel 21 having peripherally spaced teeth 22 shaped to cooperate with ratchets 23 and 24 operating in opposite directions. Ratchet 23 is mounted for free pivotal movement on a shaft 25, the shaft being journaled as indicated at 26 and 27. The shaft is extended to carry a ratchet lifter comprising a sleeve S having an arm 28 projecting therefrom to engage abutment 29 formed on the ratchet, so that upward movement of arm 28 will raise the ratchet and disengage it from the wheel 21. Movement of the ratchet lifter is effected through bifurcated arm 30 projecting from sleeve S and serving to rotatively mount a pin 31 having a transverse threaded aperture for cooperation with link 32.

At the opposite side of the wheel 21 the ratchet 24 is similarly mounted on a shaft 33, the shaft having an extension carrying a sleeve S', with a lifter 34 cooperating with an abutment 35 projecting from the ratchet, and further having a bifurcated arm 36 for mounting pin 37 which cooperates with threaded link 38.

The two links 32 and 38 are pivoted by pins 32a and 38a to a central yoke 39 which is adapted to be moved in a vertical direction by means of the control tube 40 surrounding the push rod 18 and extending upwardly through vertical propel shaft 11 and the center pin 10. A control lever 41, pivoted on a fixed bracket at 42, cooperates with the upper end of control tube 40 and serves to raise and lower the tube, the interconnection between the control lever and the tube being arranged to provide for free relative rotation about the axis of the center pin 10, so that rotative movement of the base assembly 9 is accommodated. Adjustment of the control lever is maintained by employment of a notched quadrant 43. As shown, the quadrant has four notches, corresponding to the four positions of adjustment of the ratchet mechanism referred to more fully hereinafter.

An arm 44 projects from and moves with the ratchet lifter parts 34, 36 (at the right-hand side in Figures 3 to 5), such motion being independent of ratchet 24 except when the lifter arm 34 contacts the ratchet abutment 35. Arm 44 is connected by link 45 with an arm 46 which is rigid with ratchet 23 at the opposite side. Link 45 has lost-motion slots 47 cooperating with the pins 48 and 49, by means of which the link is coupled with arms 44 and 46.

In considering the operation of the ratchet mechanism, it should be kept in mind that although the ratchet lifter arms 28 and 34 are arranged for cooperation with abutments 29 and 35 on the two ratchets to disengage the latter upon upward movement of the lifters, the ratchet lifters are movable independently of the ratchets in all positions below the point of engagement with the ratchet abutments 29 and 35. Gravity is thus relied upon for downward movement of

the ratchets into engagement with the ratchet wheel 21.

In Figure 1, indicia are applied to the four notches of quadrant 43, such indicia indicating the four positions of ratchet adjustment, the first two of which are shown in Figure 3 and the remaining two of which are illustrated, respectively, in Figures 4 and 5.

In position A, the control tube 40 is at the uppermost limit of its motion, and at that time both of the ratchet lifters 28 and 34 are operative to raise the ratchets (23 and 24) associated therewith. This position is shown in full lines in Figure 3, from which it will be seen that both of the ratchets are well clear of the ratchet wheel 21, ratchet 24 being lifted somewhat higher than ratchet 23.

Upon actuation of the control lever 41 to position B, the control tube 40 is caused to move downwardly, with the result that ratchets 23 and 24 take the positions indicated in Figure 3 at 23a and 24a. Ratchet 23 at this time is in engagement with the wheel 21, although the downward movement of ratchet 24 is still not sufficient to engage the wheel.

Further downward movement of control tube 40, accompanying movement of the control lever 41 to position C, permits ratchet 24 to drop to the position indicated in Figure 4, in which both ratchets are in engagement with the wheel 21. From Figure 4 it will also be seen that the lifter 28 at the left has moved downwardly away from the cooperating ratchet abutment 29.

From the above it will be seen that the three positions of adjustment just described are entirely effected by the ratchet lifters and the control tube which is coupled with the operating handle 41. To ensure freedom for such operation the cross link 45 is slotted sufficiently to permit the required freedom of movement between arm 46 of ratchet 23 and arm 44 of the lifter for ratchet 24. Thus, in the full line position of Figure 3 (position A) the slots 47 prevent transmission of any force between arms 44 and 46. It will also be observed that as the control tube is moved downwardly until position C is reached, as shown in Figure 4, the slots 47 in link 45 do not in any way affect the positions of the ratchets.

Upon movement to position D, however (see Figure 5), link 45 comes into play, transmitting a lifting force to ratchet 23 from the arm 44 which moves with the lifter mechanism at the right side.

Summarizing, it will be seen that in position A, both ratchets are disengaged; in position B, ratchet 23 is engaged and ratchet 24 is disengaged; in position C (Figure 4), both ratchets are engaged; and in position D (Figure 5), ratchet 23 is disengaged and ratchet 24 is engaged.

Referring again to link 45 and its lost-motion slots 47, it is pointed out that the required lost motion may be secured from only a single slot arranged at one end of the link (instead of two slots as herein illustrated), the only essential being that the extent of lost motion must be adequate to permit the desired free operation of the lifters as between any of positions A, B and C. The link, therefore, comes into operation for only one out of the four positions of adjustment (position D).

The foregoing arrangement of the ratchet lifters and other actuating parts is unusually simple as compared with prior double-acting four-position ratchet devices. In addition, for reliability of operation, it is of advantage that only one out

of the four positions relies upon a cross link between the ratchet mechanisms at opposite sides.

Attention is now directed to another important feature, in accordance with which provision is made for adjustment of the positions of the lifters with respect to the vertical control tube 40 and the yoke 39, and thus also of the positions of the ratchets when supported by the lifters.

As hereinbefore mentioned, each lifter is directly coupled with yoke 39 by means of a link (32 or 38), which link is threaded into a pin (31 or 37) carried by the lifter mechanism. Adjustment of lifter 28 may be effected merely by removing pin 32a which interconnects link 32 with control yoke 39, and by screwing link 32 up or down in pin 31 and then reconnecting the link with the control yoke. Adjustment at the opposite side may be effected in a similar manner.

In accordance with the foregoing, provision is made for adjustment so that the desired position of the ratchet lifters, and of the ratchets when raised by said lifters, may quickly and accurately be established at the time of initial assembly. Any service wear may also be compensated for in this way. It may be mentioned that accuracy of adjustment is of importance for several reasons. For example, if one or both of the ratchets are not in full engagement in accordance with the intended operating setting, heavy loads might be transmitted through the operating and control connections.

Structurally, the ratchet mechanism herein disclosed is not only simple in design but, in addition, the parts are strong and so relatively located as to take heavy loads without introducing undue bending moments or the like. Note, for example, that each ratchet (see ratchet 23 in Figures 2 and 3) is rotatively mounted on a supporting shaft, which shaft is carried in journals (26 and 27) located one at either side of the ratchet and immediately adjacent thereto.

I claim:

1. In a double-acting ratchet, in combination with a ratchet wheel and with an upright vertically movable control member, a pair of operatively opposed ratchets associated with said wheel and each pivotally mounted for downward and upward swinging movement into and out of engagement with the ratchet wheel, respectively, for each ratchet a pivoted lifter having an abutment surface adapted to cooperate with a complementary surface on the ratchet for disengaging the ratchet upon upward pivotal movement of said lifter, and, for each lifter, a link coupled therewith and with the control member, the operating parts for each ratchet being arranged to provide for lifting of one ratchet prior to lifting of the other ratchet, upon movement of the control member in one direction.

2. A construction in accordance with claim 1 in which one of said ratchets and the lifter for the other ratchet are interconnected by a pivotal lost-motion link operative upon movement of the control member in one direction to transmit a ratchet disengaging movement to said one ratchet from the lifter associated with the other ratchet.

3. A construction in accordance with claim 1 in which one of said ratchets and the lifter for the other ratchet are interconnected by a pivotal lost-motion link operative upon movement of the control member in one direction to transmit a ratchet disengaging movement to said one ratchet from the lifter associated with the other ratchet, the ratchet adjusting parts, including said lost-motion link, being arranged to provide four posi-

tions of adjustment of said ratchets upon upward and downward pivotal movement of the lifters, the highest position of said lifters providing for disengagement of both ratchets, the next or second position of said lifters providing for engagement of one ratchet and disengagement of the other, the third position of said lifters providing for engagement of both ratchets, and the fourth position of said lifters providing for disengagement of said one ratchet and for engagement of said other ratchet.

4. In a double-acting ratchet, in combination with a ratchet wheel and with an upright vertically movable control member, a pair of operatively opposed ratchets associated with said wheel and each pivotally mounted for downward and upward swinging movement into and out of engagement with the ratchet wheel, respectively, for each ratchet a pivoted lifter having an abutment surface adapted to cooperate with a complementary surface on the ratchet for disengaging the ratchet upon upward pivotal movement of said lifter, for each lifter a link coupled therewith and with the control member, and means cooperating with at least one of said links and providing for adjustment of the associated lifter device with respect to the control member.

5. For a crawler tractor, a truck lock including a pair of operatively opposed ratchets, a vertical push-pull member for controlling the positions of the ratchets, a separate operating connection between the control member and each of said ratchets including a link connected with the control member and having screw thread adjustment means for determining the position of that ratchet with reference to the vertical control member independently of the other ratchet.

6. For a crawler tractor, a truck lock including a pair of operatively opposed ratchets, a member for controlling the positions of the ratchets, a separate operating connection between the control member and each of said ratchets including, for each ratchet, separately adjustable means for determining the position of the ratchet with a given setting of the control member, whereby the relative position of the ratchets may be altered with a given setting of the control member.

7. In combination with a ratchet wheel, a pair of operatively opposed ratchets associated with said wheel, each ratchet being pivotally mounted for swinging movement upwardly and downwardly between positions in and out of cooperation with the ratchet wheel, an upright vertically movable control member for said ratchets, and mechanism associated with the control member and the ratchets for effecting different adjustments of the latter including, for each ratchet, a pivotally mounted lifter and a link connecting said lifter with said control member whereby the lifters for the two ratchets are pivotally moved upon vertical movement of the control member, each of said lifters and the ratchet with which it is associated being provided with cooperating abutments adapted to interengage upon upward pivotal movement of the lifter to effect raising of the associated ratchet, said links and the associated parts of the adjustment mechanism being arranged to provide for lifting of one of said ratchets prior to the other, upon movement of the control member in one direction.

8. A construction in accordance with claim 7 and further incorporating a pivoted lost-motion

link interconnecting one of said ratchets and the lifter for the other of said ratchets.

9. In combination with a pair of operatively opposed ratchets, mechanism for controlling the positions of the ratchets including, for each ratchet a lifter movable with respect to the ratchet but adapted to abut the ratchet upon upward movement to transmit a lifting force thereto, control means for raising and lowering said lifters conjointly, the ratchets and lifters being arranged to provide for lifting of one ratchet prior to the other upon conjoint upward movement of the lifters, whereby in an upper position of adjustment the lifting members act to disengage both ratchets, in the next lower or second position of the lifters one ratchet is engaged and the other disengaged, and in a still lower third position both ratchets are engaged, and means operative upon conjoint downward movement of the lifters from said third to a

fourth position for disengaging the ratchet which was engaged in the second position, the other ratchet remaining engaged.

10. A construction in accordance with claim 5 and further incorporating means for adjusting the position of the lifters with respect to the control means.

11. A construction in accordance with claim 9 and further incorporating means for adjusting 10 the position of the two lifters with respect to the control means independently of each other, whereby the relative position of the ratchets is adjustable.

12. A construction in accordance with claim 15 9 in which said last means comprises a lost-motion link connecting the ratchet which is engaged in the second position with the lifters for the other ratchet.

CECIL E. JONES.
